UNITED STATES PATENT OFFICE.

ALBERT S. CAHN AND JOHN W. JOHNSON, OF KANSAS CITY, MISSOURI.

ANTISKIDDING DEVICE.

1,118,102.

Specification of Letters Patent. Patented Nov. 24, 1914.

Application filed December 22, 1911. Serial No. 667,304.

To all whom it may concern:

Be it known that we, ALBERT S. CAHN and JOHN W. JOHNSON, citizens of the United States, residing at Kansas City, in the county of Jackson and State of Missouri, have invented certain new and useful Improvements in Antiskidding Devices, of which the following is a specification.

This invention has relation to anti-skidding devices especially adapted to be used upon automobiles, and has for its object to provide a device of simple structure in the form of an attachment which may be easily and quickly applied to the frame or supporting members of the automobile. The parts are so arranged that the working members of the anti-skidding device may be brought in contact with the surface of a street or roadway by the use of a foot lever or treadle, while at times when the use of the anti-skidding device is not necessary the said wheels remain elevated above the surface of the street or roadway.

With the above objects in view the attachment includes clips adapted to be applied to the axle or other supporting members of the frame of the automobile. Arms are pivotally connected with the said clips and a spacing member is interposed between the arms. A shaft is carried at the free ends of the arms and serves as means for connecting the free ends of the said arms together. The free ends of the arms are slotted and wheels having roughened peripheries are located in the said slots and are journaled upon the said shaft. A foot lever or treadle mechanism is provided for swinging the attachment so that the wheels carried thereby may be brought in contact with the surface of the street or roadway and thereby prevent skidding of the machine.

A still further object of the invention is generally to improve this class of devices so as to increase their utility, durability and efficiency.

Further objects and advantages will appear in the following description, it being understood that various changes in form, proportions and minor details of construction may be resorted to within the scope of the appended claim.

For a full understanding of the invention reference is to be had to the following description and accompanying drawing, in which:

Figure 1 is a side elevation of an auto-

mobile with one of the rear wheels removed showing the device applied; Fig. 2 is a perspective view of the anti-skidding device.

Corresponding and like parts are referred to in the following description and indicated in all the views of the accompanying drawing by the same reference characters.

The anti-skidding device comprises clips 1 which are adapted to be bolted or otherwise secured upon the axle or other parts of the frame of an automobile in the vicinity of the rear axle thereof. A bar 2 is interposed between arms 3 and serves as means for positively holding the clips spaced from each other at a suitable predetermined distance. Arms 3 are pivoted between the opposite side portions of the clips 1 and are located beyond the ends of the cross bar 2. The said arms 3 are provided at their free end portions with longitudinally disposed slots 4. A shaft 5 which tapers from its extremities to form a central enlarged portion, as shown connects the free end portions of the arms 3 together but passes transversely across the slots 4 provided therein, the extremities of the arm extending across the slots being rounded. The said shaft 5 is held against longitudinal movement by means of cotter pins 6 or other suitable securing devices which are mounted upon the said shaft and which bear against the sides of the arms 3. Wheels 7 are journaled upon the rounded extremities of the shaft 5 and are received within the slots 4 of the arms 3. These wheels are provided with roughened peripheries and in general appearance resemble ordinary sprocket wheels. Braces 8 disposed one within the other extend between the intermediate enlarged flattened portion of the shaft 5 and the intermediate portions of the arms 3 and serve as means for effectually bracing the structure, the bar 2 extending through the extremities of one of said braces.

The free end portions of the arms 3 are normally held in elevated positions with relation to the surface of the ground by means of coiled springs 9 which are connected with the said arms 3 and with rigid portions of the frame of the automobile. A foot treadle or lever 10 is fulcrumed upon the frame of the automobile within reach of one occupying the driver's seat, and a rod 11 connects the said lever 10 with the shaft 5.

From the above description it will be seen that when the lever 10 is swung the rod 11

will move longitudinally, whereby the arms 3 are swung and the roughened peripheries of the wheels 7 are brought into contact with the surface of the street or roadway. 5 The teeth or roughened parts at the peripheries of these wheels will bite into the pavement or roadway sufficiently to prevent the machine from skidding laterally as it goes around curves or corners. At the same time 10 the pressure through the lever 10 will not be sufficient to cause the teeth upon the peripheries of the wheels 7 to damage or mar the surface of the street or roadway. As soon as the machine has passed around a curve 15 or has proceeded to such an extent where skidding is unlikely or impossible, pressure is removed from the lever 10, when the tension of the springs 9 comes into play and the arms 3 are swung so that the wheels 7 are elevated above the surface of the street or roadway.

Having thus described the invention, what is claimed as new is:

25 An anti-skid device including pivotally mounted arms, each of said arms terminating in spaced prongs, a shaft connecting the arms and being reduced and rounded at each

extremity to extend transversely through the prongs, wheels journaled upon the rounded extremities of the shaft, one between the 30 prongs of each arm, the shaft being centrally enlarged and flattened, a pair of diagonal braces secured centrally and one within the other to the central enlarged flattened portion of the shaft, the extremities of said braces diverging and having their terminals secured in spaced relation to the intermediate portions of the arms, a brace extending parallel to the shaft and having its ends passed through the ends of 40 one of the first-mentioned pair of braces and through the arms to secure said brace in place, a lever arm secured upon one end of the shaft, and means operatively connected with the lever arm for swinging said spaced 45 arms.

In testimony whereof we affix our signature in presence of two witnesses.

ALBERT S. CAHN. [L.S.]
JOHN W. JOHNSON. [L.S.]
